UNITED STATES PATENT OFFICE.

GARDNER HOWLAND, OF BRUNSWICK, NEW YORK.

IMPROVEMENT IN BRICK-KILNS.

Specification forming part of Letters Patent No. 129,959, dated July 30, 1872.

Specification of an Improvement in the Manufacture of Bricks, invented by GARDNER HOWLAND, of Brunswick, in the county of Rensselaer and State of New York.

In the accompanying drawing, Figure 1 is a perspective view of the kiln. Fig. 2 is a sectional view of the bottom of the column, showing the method of supporting it and its appearance while the burned bricks are being taken out, the kiln being left out of the drawing to give an unobstructed view.

It is well understood that the main difficulty in the manufacture of brick by the present mode is the inequality of their burning, some being burned too much so as to melt and run together, while a large portion of those on the outer portions of the kiln are burned insufficiently, or not burned at all, causing great loss in both overburned and underburned brick, and throwing a heavy tax for labor and material upon the portions that are well burned; and another difficulty is experienced in the delay of operations between the preparation and construction of a kiln and its burning, being alternate, occupying several days or weeks, and causing great loss of time.

By my improvement these different operations are continuous in all their parts, and every brick is burned to its desired consistency.

My invention consists in arranging a column of brick prepared for burning, in a kiln constructed for the purpose, in such a manner that the column may be lowered, passing a reverberatory furnace, where they are burned, and below it, where they are cooled, and taken out at the bottom of the column, while, at the same time, fresh brick are added at the top of the column, being a continuous process. And to enable others skilled in the art to construct and use my invention, I will proceed to describe its construction and operation.

Figure 1 represents a kiln made with brick, about twenty-five feet high and four or eight feet square, larger if desired, with a reverberatory furnace, B, situated about midway or a little below the center, and openings D at the bottom of the kiln, where the brick are taken out. a, b, c, and d are jack-screws set a little way in from the corners and supporting the column. To commence the operation, blocks of timber or plank may be placed upon these screws and bricks placed upon them

till the kiln is filled up to the furnace, where unburned brick, or brick ready to be burned, may be filled in until they reach the top of the kiln, when a fire may be started in the reverberatory furnace, throwing its heat and smoke into the kiln and through the column of brick thus prepared until the brick nearest the fire are sufficiently burned and the column is ready to be lowered. In the operation of lowering the column one man may enter the aperture D and lower the screw c; at the same time another man will lower the screw a at the opposite corner of the column, and each man remove his block and the brick that may be loosened by lowering the screw, and then turn the screws a and c up again until they firmly hold the column, when the screws b and d may be lowered in like manner and the bricks removed, when b and d are again screwed up till they hold the column equally with a and c, when all the screws are lowered simultaneously and the column follows them down until the brick that are not sufficiently burned come opposite the reverberatory furnace, where they are allowed to remain until they are sufficiently burned, when they are again lowered and the brick removed and the first operation repeated. In the meantime the top of the column at F, and under the roof H, is constantly receiving a supply of brick prepared for burning, and piled upon it in the order that is requisite to admit of draft, and such a free admission of the heat around and between each brick as will insure perfect burning. Here, also, may be added, if desired, fine coal to facilitate its burning and assist the furnace in effecting the requisite heat. This may be determined and regulated by the operators, as different circumstances may require. This column should be kept filled above the top of the kiln, where it is more easy of access while the smoke and steam are escaping through the brick. Where it is desired to use a larger kiln a fifth screw may be placed in the center of the base of the column, which will diminish the size of the arch opened by lowering the screws and loosen a smaller quantity of brick when each screw is loosened. Thus any size kiln may be operated by the addition of a greater number of screws and increasing the size and number of the furnaces, placing one or more on either

side, as may be deemed necessary. This kiln may be built in the side of a hill, with the yard on the upper side level with the top of the kiln, which I prefer, as it can be operated with less expense; or it may be placed on a level ground and the unburned brick elevated to the top of the kiln.

I do not confine myself to any particular height of column, that being determined by the character of the material used and the size of the articles to be burned.

By my arrangement of the furnaces in or about the center of the kiln, with openings at the bottom, a current of cold air enters the kiln through said openings, passes around and through the brick resting on the jacks, which,

though done, are still hot. These brick are cooled by the current of air, which afterward becomes highly heated as it passes up opposite the furnaces, where the brick are subjected to a white heat, and thence passes out of the kiln, consuming everything that is combustible.

I claim as new and of my invention—

The arrangement in a brick-kiln of the furnaces B B, openings D D, and jack-screws *a b c d*, constructed and operating as and for the purpose set forth.

GARDNER HOWLAND.
